UNITED STATES PATENT OFFICE.

TRYGVE S. HANNES AND RALPH HANNES, OF SAN DIEGO, CALIFORNIA.

WRENCH.

Application filed September 10, 1926. Serial No. 134,665.

Our invention relates to wrenches, and more particularly to socket wrenches, although we desire it to be understood that our invention is applicable to wrenches other than 5 socket wrenches.

The objects of our invention are: first, to provide a unitary wrench having a multiplicity of wrench members adapted to be readily adjusted relative to each other so as 10 to independently fit nuts, bolts, or other members of various sizes for turning the same; second, to provide a wrench having a multiplicity of axially shiftable telescoping wrench members adapted to be independently 15 extended beyond one end of the wrench so as to fit nuts, bolts, or other members of different sizes when the separate wrench members are extended; third, to provide a compact unitary socket wrench adapted to fit nuts, 20 bolts, or other members of various sizes, and a wrench of this class having ratchet means whereby the handle means may be connected with the wrench members so that the latter may be intermittently rotated in one direction 25 or the other, and whereby the handle means may be extended longitudinally relative to the wrench members so that the wrench may be used in deep recesses; fourth, to provide a wrench of this class from which 30 none of the parts may be readily lost; fifth, to provide a novel and simple means for adjusting and locking the several wrench members relative to each other in a multiple wrench of the class mentioned; sixth, to provide 35 a wrench having a multiplicity of inter-shiftable telescoping wrench members adapted to be used one at a time, said wrench members being rigidly mounted with respect to each other and adapted to be longitudinally 40 guided and locked against rotatable movement relative to each other; seventh, to provide a wrench in which the handle thereof, when shifted in one direction, is adapted to rotate the wrench member in one direction 45 and, when shifted to the opposite side of the wrench member, is adapted to shift the latter in the opposite direction; eighth, to provide a wrench of this class whereby the wrench member may be rotated in either direction by 50 the handle when the latter is longitudinally extended relative to the former; ninth, to provide as a whole a novelly constructed wrench of this class; and, tenth, to provide a wrench of this class which is simple and 55 economical of construction proportionate to its function, durable, efficient, easy to adjust

and manipulate and which will not readily deteriorate or get out of order.

With these and other objects in view, as will appear hereinafter, our invention consists of certain novel features of construction, combination and arrangement of parts and portions, as will be hereinafter described in detail and particularly set forth in the appended claims, reference being had to the accompanying drawings and to the characters of reference thereon which form a part of this application in which:

Figure 1 is a top view of our wrench showing the handle fragmentarily and extended to its operative position at a right angle to the axes of rotation of the wrench members; Fig. 2 is a side elevational view thereof; Fig. 3 is a fragmentary side elevational view thereof showing the handle extended in line with the wrench members so that the wrench may be used for tightening and unloosening nuts and the like in deep recesses, or ordinarily inaccessible portions; Fig. 4 is another side elevational view of the wrench taken from the front side, or at a right angle to that shown in Fig. 2; Fig. 5 is a longitudinal sectional elevational view thereof taken through 5—5 of Fig. 2, certain parts and portions being shown in elevation to facilitate the illustration and other parts being shown by dotted lines shifted to other positions; Fig. 6 is a fragmentary longitudinal sectional elevational view thereof taken through 6—6 of Fig. 1, also showing certain parts and portions in elevation to facilitate the illustration; Fig. 7 is a sectional view thereof taken through 7—7 of Fig. 2; Fig. 8 is a partial sectional view and partial top view thereof taken at 8—8 of Fig. 2; Figs. 9 and 10 are transverse sectional views thereof taken respectively through 9—9 and 10—10 of Fig. 6, and Fig. 11 is a fragmentary sectional view thereof taken through 11—11 of Fig. 8, showing the shifting of the pawls to inoperative position by the handle.

Like characters of reference refer to similar parts and portions throughout the several views of the drawings.

The outer socket member 1, socket members 2, 3 and 4, guide and stop member 5, screw 6, ratchet 7, wrench rotating member 8, retaining and guide plates 9 and 10, screws 11, pawls 12 and 13, pins 14, pawl springs 15, handle 16, pivot members 17, 105 wrench member adjusting screws 18, 19 and 20, adjusting screw rotating key or plunger 110

guide 21, adjusting screw rotating key, or plunger 22, knob 23, compression spring 24 and the handle member 25 constitute the principal parts and portions of our wrench in its preferred form of construction.

The outer wrench member or socket 1 is preferably made cylindrical or slightly tapered toward its lower end and is preferably provided with a hexagonal recess 1^a extending inwardly from its lower or small end. The wrench or socket members 2, 3 and 4 are of similar construction and the latter fitting respectively within the former and the wrench or socket member 2 fitting within the wrench member 1. Said wrench members 2, 3 and 4 are preferably made of hexagonal tubes of such sizes that the inner tubes may be readily shifted axially with respect to the adjacent outer tubes. It will be here noted that the wrench or socket members are adapted to fit hexagonal nuts, bolts, or other members. It is obvious that the tubes or wrench members of other cross section may be similarly used and combined to fit nuts, bolts or other members of different shapes. The outer or normally lower ends of all of the wrench members are preferably slightly tapered or rounded at said ends so as to permit the wrench members to be inserted into small recesses.

Spaced from the outer or lower end of the wrench member 1 and extending transversely through the central portion thereof, is a guide and stop member 5 which is secured in position by means of a screw 6 extending through a flange portion 5^a at the one end of the member 5 and into the member 1, as shown best in Fig. 5. Said member 5 extends also through longitudinal slots in the wrench or socket members 2, 3 and 4, as shown in Figs. 5, 6 and 10, permitting said wrench or socket members to be shifted axially with respect to the member 1 but also prevents said wrench or socket members to be withdrawn from the member 1. The guide and stop member 5 also takes the torsional strains from the adjacent outer wrench member from the wrench member on which the initial strain is applied.

The upper enlarged end of the wrench member 1 is reduced and provided with a reversible ratchet 7 having rectangular longitudinal grooves in its periphery. Around the ratchet is rotatably mounted the wrench rotating member 8 which is in the form of an annular collar having extended portions 8^a at its diametrically opposite sides. The rotating member or collar 8 is retained in position against the shoulder, formed by the reduced portion of the member 1, by the retaining member 9, which, together with the retaining member 10, is secured to the upper end of the wrench member 1 by screws 11.

In the extended portions of the collar 8, are provided slots which extend transversely with the axis of rotation of the collar. In

said slots, at the opposite sides of the collar, are pivotally mounted the pawls 12 and 13, by means of pivot pins 14, as shown best in Figs. 6 and 8. The one ends of the pawls 12 and 13 are normally forced into engagement with the grooved or notched portions of the ratchet by means of plate springs 15 mounted in grooves at the periphery of the collar, as shown best in Figs. 4 and 8. The free ends of the springs 15 engage the opposite ends of the pawls and normally force said ends outwardly from the collar 8, as shown best in Figs. 1 and 8. The outer ends of said pawls are provided with enlarged portions 12^a and 13^a respectively, which portions extend transversely with the pawls and parallel with their pivotal axes and are considerably rounded at their outer sides, as shown in Figs. 1, 4, 8 and 11.

The handle 16 is bifurcated at its one end and is adapted to receive in the bifurcated portion the collar 8. The ends of the furcations are provided with pivot pins or trunnions 17, which extend into diametrically opposite holes 8^b in the annular member or collar 8, said holes being positioned intermediate the extended portions of the annular member or collar, as shown in Fig. 8. Thus the handle 16 is pivotally connected to the annular member or collar 8 so that the former may swing to either side of the latter, or to any intermediate position relative to the latter. When the handle is shifted to the position shown in Figs. 1, 2, 6 and 8, the same is adapted to engage the outer end of one of the pawls and disengage said pawl from the ratchet, as shown in Fig. 8, and when the handle is shifted to the opposite side of the annular member or collar, the same is adapted to release the formerly depressed pawl and engage the other pawl, correspondingly depressing the same and disengaging the opposite end thereof from the ratchet, thus permitting the ratchet to be rotated in either direction by the ratchet and pawl means when the handle is shifted to its opposite positions relative to the member 8, as stated. The handle 16 is provided with a cam or rounded portion 16^a at the point of engagement thereof with the outer ends of the pawls so that the pawls are more readily depressed when engaged by the handle, as shown in Figs. 8 and 11.

The arms or furcations 16^b of the handle are preferably made of separate members and secured to the main portions 16^a of the handle by means of screws 16^c, so that the pivot pins or trunnions 17 may be readily renewed when necessary.

In the upper or head end of the wrench or socket member 1, are rotatably mounted the head ends of a plurality of wrench member adjusting screws 18, 19 and 20, respectively for adjusting the wrench members 2, 3 and 4. At the upper or inner ends of the wrench or socket members 2, 3 and 4, are provided in-

wardly extending portions or sockets 2^a, 3^a and 4^a respectively, into which the adjusting screws extend for adjusting said wrench members, said portions 2^a, 3^a and 4^a being also adapted to prevent the removal of said wrench members from the main, or outer wrench member 1. The portions 2^a, 3^a and 4^a are also so shaped as to readily slide past each other when adjusting the separate wrench members inwardly or outwardly. The screws 18, 19 and 20 are provided with large pitch or multiple threads so that the wrench members may be quickly adjusted inwardly or outwardly.

The retaining member 9 at the upper end of the wrench member 1 is provided at its upper side with a transverse groove 9^a in which is reciprocally mounted the slide 21, said slide being retained in position in said groove by the retaining member or plate 10 positioned at the outer side of the member 9. The retaining member 10 is provided with a transverse slot 10^a, coincident with the groove 9^a, through which the outer end of the slide 21 extends. At the inner portion of the slide 21 is reciprocally mounted a plunger or screw adjusting key 22 which is provided with a reduced stem extending beyond the upper end of the slide and to which is secured a knob 23. Around the stem 22^a is positioned a compression spring 24 which engages the shoulder at the lower portion of the key and is adapted to force the key portion 22^b at its inner end into the slots in the heads of the adjusting screws, as shown best in Fig. 5. It will be here noted that the inner ends of the adjusting screws are rotatably mounted at the upper side of the guide member 5.

The wrench or socket member 4, adjustable by means of the screw 20, is shown in its outer or operative position for rotating a small nut or bolt. In order to adapt the wrench for a larger size nut or bolt, the member 4 is screwed inwardly by rotating the screw 20 in the proper direction; then the knob 23 is withdrawn, disengaging the key 22 from the head of the screw 20, and shifted opposite the head of the screw 19 and released; the knob 23 is then rotated in the proper direction so that the wrench or socket member 3 is forced outwardly, as shown by dotted lines in Fig. 5. If the wrench is to be adapted for the next size nut or bolt, the wrench member 3 is shifted inwardly and the member 2 forced outwardly. It will be here noted that the wrench members cannot be shifted inwardly without manipulation of the adjusting screws by reason of the heads of said screws being retained in position by the retaining member 9, said member 9, however, being provided with holes opposite the heads of said screws through which said key 22 is adapted to extend. It will be here also noted that, if desired, the outer wrench member or socket 1 may be extended at its lower end so that when all of the inner wrench members or sockets 2, 3 and 4 are drawn in-

wardly, the outer wrench member or socket may serve as a wrench for still larger nuts or bolts.

When desiring to rotate a nut or bolt in a recess of considerable depth, the handle 16 is shifted to a position intermediate the right angle positions of the handle previously referred to or to the position in alignment with the longitudinal axis of the wrench members, as shown in Fig. 3. In the latter case, the annular member or collar is positively locked relative to the outer wrench member 1 so that the wrench members are rotated irrespective of the direction of rotation of the handle. When the wrench is used as last stated, a handle member 25 is extended through a hole 16^a extending transversely through the outer portion of the handle, as shown in Figs. 1 and 3. The handle member 25 may be merely a rod, or a rod provided with spaced apart keys 25^a which are adapted to retain the handle member within the outer end of the handle 16. The hole 16^a at the outer end of the handle is preferably slotted at one side so as to permit one of the keys 25^a to be extended therethrough. After the handle member 25 is inserted through the hole in the handle, as stated, the handle member 25 is rotated a portion of a revolution and thus retained in position.

Though we have shown and described a particular construction, combination and arrangement of parts and portions, we do not wish to be limited to this particular construction, combination and arrangement, but desire to include in the scope of our invention the construction, combination and arrangement substantially as set forth in the appended claims.

Having thus described our invention, what we claim as new and desire to secure by Letters Patent is:

1. In a wrench, an outer socket, a plurality of other sockets mounted within the outer socket, an annular member mounted on said outer socket, reversible ratchet and pawl means operatively connecting said annular member with said outer socket, a handle pivotally connected to said annular member, and means in connection with said handle and said ratchet and pawl means whereby said ratchet and pawl means is reversed when said handle is shifted from one position to its opposite position relative to said annular member.

2. In a wrench, an outer socket, a plurality of other sockets mounted within the outer socket, an annular member mounted on said outer socket, reversible ratchet and pawl means operatively connecting said annular member with said outer socket, a handle pivotally connected to said annular member, and means in connection with said handle and said ratchet and pawl means whereby said ratchet and pawl means is reversed when said

handle is shifted from one position to its opposite position relative to said annular member and whereby said annular member is positively locked with said outer socket when said handle is shifted to an intermediate position.

3. In a wrench, an outer socket, socket wrench members telescopically mounted within said outer socket, and screw means extending within said outer socket in connection with said socket wrench members for adjusting the same axially with respect to each other.

4. In a wrench, an outer socket, socket wrench members telescopically mounted within the outer socket, screw means extending within said outer socket in connection with said socket wrench members for adjusting the same axially with respect to each other, and ratchet and pawl means in connection with said outer socket for rotating the same.

5. In a wrench, a main wrench member, a plurality of axially shiftable wrench members telescopically mounted with respect to said main wrench member, adjusting screws in connection with said main wrench member and each of said inter-shiftable wrench members, and means in connection with said main wrench member adapted to be shifted transversely therewith and adapted to engage and actuate each of said screws independently of each other.

6. In a wrench, a main wrench member, a plurality of axially shiftable wrench members telescopically mounted with respect to said main wrench member, adjusting screws in connection with said main wrench member and each of said inter-shiftable wrench members, and means in connection with said main wrench member adapted to be shifted transversely therewith and adapted to engage and actuate each of said screws independently of each other, and means for rotating said main wrench member.

7. In a wrench, a wrench member, and a handle rotatably mounted on said wrench member on an axis coincident with the longitudinal axis of said wrench member and also pivotally mounted on said wrench member on an axis transverse with the longitudinal axis of the latter.

8. In a wrench, a wrench member, a handle means rotatably mounted on said wrench member on an axis coincident with the longitudinal axis of said wrench member and also pivotally mounted on said wrench member on an axis transverse with the longitudinal axis of the latter, and ratchet and pawl means in connection with said wrench member and said handle means for operatively connecting the latter with the former whereby said wrench member may be rotated in one direction when the handle means is tilted in one direction about its pivotal axis and whereby said wrench member may be rotated in the

opposite direction when said handle means is tilted in the opposite direction about its pivotal axis.

9. In a wrench, a wrench member, a handle means rotatably mounted on said wrench member on an axis coincident with the longitudinal axis of said wrench member and also pivotally mounted on said wrench member on an axis transverse with the longitudinal axis of the latter, and ratchet and pawl means in connection with said wrench member and said handle means for operatively connecting the latter with the former whereby said wrench member may be rotated in one direction when the handle means is tilted in one direction about its pivotal axis and whereby said wrench member may be rotated in the opposite direction when said handle means is tilted in the opposite direction about its pivotal axis, and also whereby said handle is positively locked relative to said wrench member when the former is shifted to an intermediate position.

10. In a wrench, a wrench member, an annular member rotatably mounted on said wrench member, a handle member pivotally connected to said annular member on an axis transverse with the axis of rotation of said annular member, and ratchet and pawl means operatively connecting said annular member with said wrench member, the pawls of said ratchet and pawl means being provided with extended portions adapted to be engaged by said handle when the latter is shifted to opposite positions relative to said annular member for variously connecting said annular member with said wrench member for rotating the latter.

11. In a wrench, a wrench member, an annular member rotatably mounted on said wrench member, a handle member pivotally connected to said annular member on an axis transverse with the axis of rotation of said annular member, and ratchet and pawl means operatively connecting said annular member with said wrench member, the pawls of said ratchet and pawl means being provided with extended portions adapted to be engaged by said handle when the latter is shifted to opposite positions relative to said annular member for variously connecting said annular member with said wrench member for rotating the latter, the extended portions of said pawls being disengaged from said handle when the latter is shifted to an intermediate position whereby said annular member is positively locked relative to said wrench member.

12. In a wrench, a wrench member, an annular member rotatably mounted on said wrench member, a handle member pivotally connected to said annular member on an axis transverse with the axis of rotation of said annular member, ratchet and pawl means operatively connecting said annular member

with said wrench member, the pawls of said ratchet and pawl means being provided with extended portions adapted to be engaged by said handle when the latter is shifted to opposite positions relative to said annular member for variously connecting said annular member with said wrench member for rotating the latter, the extended portions of said pawls being disengaged from said handle 10 when the latter is shifted to an intermediate position whereby said annular member is positively locked relative to said wrench member, and a handle member extending transversely through the outer end of said handle for rotating the same and said wrench member when the former is shifted to an intermediate position.

13. In a wrench, a wrench member, a handle pivotally mounted at its one end at the one end of said wrench member, ratchet and pawl means in connection with said wrench member and said handle for operatively connecting the latter with the former whereby said wrench member may be rotated in one direction when the handle is tilted to one position about its pivotal axis and whereby said wrench member may be rotated in the opposite direction when said handle is tilted to its opposite position about its pivotal axis, and 25 also whereby said handle is positively locked relative to said wrench member when the former is shifted to an intermediate position.

tion, and a handle member extending transversely through the outer end of said handle for rotating the same and said wrench member when the former is shifted to an intermediate position. 35

14. In a wrench, an outer socket, a plurality of axially shiftable wrench members telescopically mounted with respect to said outer socket, individual screw means revolvably mounted within the outer socket for independently shifting each wrench member, and means mounted on the top of said outer socket adapted to be shifted into engagement with each of said screw means for actuating same. 40

15. In a wrench, an outer socket, a plurality of axially shiftable wrench members telescopically mounted with respect to said outer socket, longitudinal slots in said wrench members, a guide member extending transversely through the wrench members and said longitudinal slots, adjusting screws longitudinally mounted within the outer socket and pivoted at their lower end on said guide member and adapted to shift said wrench members independently, and means for actuating said adjusting screws. 50

In testimony whereof, we have hereunto set our hands at San Diego, California, this 28th day of August, 1926. 55

TRYGVE S. HANNES.
RALPH HANNES.
